US0D1010315S

(12) **United States Design Patent** (10) **Patent No.:** **US D1,010,315 S**
(45) **Date of Patent:** **** Jan. 9, 2024**

(54) **SURGICAL MICROSCOPE**

(71) Applicant: **Carl Zeiss Meditec AG**, Jena (DE)

(72) Inventors: **Christof Meier**, Uttenreuth (DE);
Daniel Kolster, Oberkochen (DE)

(73) Assignee: **Carl Zeiss Meditec AG**, Jena (DE)

(**) Term: **15 Years**

(21) Appl. No.: **29/718,712**

(22) Filed: **Dec. 27, 2019**

(57) **CLAIM**

The ornamental design for a surgical microscope, as shown and described.

DESCRIPTION

FIG. 1 is a perspective view of the surgical microscope of our new design;

FIG. 2 is a front elevation view of the surgical microscope of FIG. 1;

FIG. 3 is a rear elevation view of the surgical microscope of FIG. 1;

FIG. 4 is a left side elevation view of the surgical microscope of FIG. 1;

FIG. 5 is a right side elevation view of the surgical microscope of FIG. 1;

FIG. 6 is a top plan view of the surgical microscope of FIG. 1; and,

FIG. 7 is bottom plan view of the surgical microscope of FIG. 1.

1 Claim, 7 Drawing Sheets
